W. H. BURKE

COTTER PIN PULLER

Filed May 28, 1925

William H. Burke,

WITNESS:-

Chas. L. Giesbauer

By Harrison M. Brooks Attorney

UNITED STATES PATENT OFFICE.

WILLIAM H. BURKE, OF WINNER, SOUTH DAKOTA, ASSIGNOR BY DIRECT AND MESNE ASSIGNMENTS, TO THE BURGAN CORPORATION, OF CHICAGO, ILLINOIS, A CORPORATION OF ILLINOIS.

COTTER-PIN PULLER.

Application filed May 28, 1925. Serial No. 33,556.

This invention relates particularly to a tool for extracting cotter pins, keys and like pin-like elements from a machine element or part, the object of the improvements being 5 to provide a tool which will enable the user to expeditiously remove the cotter pin by a single operation of the hand.

The invention further aims to provide a cotter pin puller by which an extracting 10 force is applied to a pair of gripping jaws after the latter have been closed against the pin.

Further, the invention resides in the provision of a combined jaw-closing and power- 15 applying means whereby, upon a single operation, the gripping jaws will first be rendered operative and then moved away from the machine part, carrying the pin with it.

20 The invention further resides in the salient features of construction, and the arrangements and combinations of parts hereinafter described in detail and claimed succinctly, reference being made to the accompanying drawing depicting the preferred embodiment of my invention, and wherein

25 Figure 1 is a front elevation of my improved cotter pin puller, illustrating the same inoperative and showing in dotted lines the closing of the jaws upon the initial movement of the handles toward each other;

Fig. 2 is a side elevation thereof;

30 Fig. 3 is a front elevation of the tool fully operative or with the cotter pin extracted; and

35 Figs. 4 and 5 are detailed cross sectional views taken on lines 4-4 and 5-5, respectively, of Fig. 1.

40 Referring more in detail to the accompanying drawings, the numeral 1 designates the jaw lever to which the power lever 2 is pivoted at 3 and deflected thereacross in the form of a shorter arm later to be referred to.

45 The jaw lever is broadened about the pivot 3 and formed with an offset, integral jaw 4, the offset forming a shoulder 5 on which is pivoted at 6 a movable jaw 7. The outer end of the movable jaw terminates in

a point or hook 8 inturned to oppose an 50 anyil-like point 9 on the fixed jaw.

Pivoted to the outer end of the shorter arm of the power lever, as at 10, is a fulcrum member 11 which is channeled to embrace the movable jaw and have slidable, guiding 55 and bearing relation therewith as will be more fully set forth hereinafter. The fulcrum member has a rigidly carried arm or strap 12 extending about the outer or back edge of the fixed jaw 4 and on opposite 60 sides of both jaws, and is designed to ride and bear on said back edge 13, riding from a recess or seat 15 up over an abrupt rise or shoulder 14. The fulcrum member has a laterally extending pin 16 designed to engage 65 a lug 17 projecting from the pivoted end of the movable jaw 7, as depicted in Fig. 1.

In operation, the handle ends of levers 1 and 2 are separated widely, as in Fig. 1, wherein it will be noted that the pin 16 has 70 moved against lug 17 and opened the movable jaw away from the fixed jaw 4, in which position the outer end of the strap 12 is engaged in the recess or seat 15. Upon closing the handles, the initial operation 75 moves the pin 16 from the lug 17 and would leave the movable jaw free to swing were it not for the fact that the outer end of the strap 12 concurrently rides up the cam shoulder 14 and pulls the fulcrum member 80 over against the outer end of said movable jaw and pushes it into cooperative relation with the fixed jaw, as depicted in the dotted showing in Fig. 1. Further closing movement of the handles retains the jaws locked 85 shut, by reason of the sleeve-like or ring-like member 12 riding over the cam surface 13 (which is substantially parallel to the movement of the fulcrum member), and the fulcrum member is brought into bearing 90 contact with the machine part, following which the gripping jaws will move bodily away from said machine part, carrying the pin with them.

Upon opening the handles, the embracing member 12 slides off the cam surface into its seat 15 and simultaneously therewith the pin 16 kicks the lug 17 to separate the jaws

for releasing the cotter pin just extracted.

The construction is exceedingly simple and durable, the strap member 12 not only closing the movable jaw but also prevents the fulcrum member from swinging out of position as well as serving to steady the same when the tool is fulcrumed thereon.

While I have described my extractor or puller in connection with cotter pin removal, the same may be applied to many similar uses and with a slight change in the shape of the jaws the device may be utilized in the removal of keys from shafts, cross pins and like machine elements. Obviously, the design and arrangement of the several parts may be changed as permitted within the scope of the appended claims and without departing from the spirit of my invention.

What is claimed is:

1. A pulling tool comprising pivoted cross handles, one end of one handle being formed with an integral jaw, a fulcrum member pivoted to the corresponding end of the companion handle, and a movable jaw closable against the integral jaw by the fulcrum member.

2. A cotter pin puller comprising a pair of levers pivotally connected to provide manipulating handles and power arms, a jaw on the power arm of one lever, a fulcrum member connected to the power arm of the companion lever, and means operable by and during relative movement between the jaw and the fulcrum member for cooperating with said jaw to grip an interposed cotter pin.

3. A cotter pin puller comprising a pair of levers pivotally connected to provide handles on one end and power arms on the opposite end, a jaw on the power arm of one lever, a movable jaw pivoted to said last-named lever for cooperation with said first mentioned jaw, and means operable by the power arm of the companion lever for engaging both jaws to close them.

4. A cotter pin puller comprising pivotally connected levers providing operating levers and oppositely disposed power arms, one power arm having a cam surface, a jaw fixed on the latter arm, a cooperating jaw movably connected to the fixed jaw, and means operable by the power arm of the companion lever and coacting with the cam surface to close the movable jaw against the fixed jaw.

5. A cotter pin extractor comprising a pair of levers pivotally connected to form handles on one end and power arms on the opposite end, a jaw fixed on the power arm of one lever, a cooperating jaw movably connected to the latter, means operable by the other power arm and slidably embracing the two jaws for closing the latter, and means for opening the jaws when the first means is inoperative.

6. A cotter pin puller comprising a shank carrying a fixed jaw one one end, a cooperating jaw pivoted on the shank, means for closing the jaws, and means for exerting a pull on the closed jaws.

7. A cotter pin puller comprising a pair of cooperating jaws movably connected, means for exerting a pull on the jaws, and means for locking the jaws closed by and during actuation of the first means.

8. A cotter pin puller comprising a fulcrum member, a lever pivoted thereto, a pair of gripping jaws operatively connected together and pivoted as a unit to said lever, and means carried by the fulcrum member to cooperate with the jaws for operating the same.

9. A cotter pin puller comprising a fulcrum member, a lever pivoted thereto, a pair of gripping jaws operatively connected together and pivoted as a unit to said lever, one jaw having a cam portion, and means carried by the fulcrum member and cooperating with the cam portion of the jaw for closing the latter against the companion jaw.

10. A cotter pin puller comprising a fulcrum member, a lever pivoted thereon, a gripping jaw extending alongside the fulcrum member and formed with a cam portion having an initial abrupt rise, a cooperating jaw interposed between the first jaw and the fulcrum member and adapted to be backed by the latter whereby the first jaw may be moved against the second jaw for gripping an object, and means carried by the fulcrum member for coacting with the cam portion of the first jaw to effect a closing together of the jaws and then hold them so closed during the lifting of the lever on its fulcrum member to pull on the object.

11. A cotter pin puller comprising a fulcrum member, a lever pivoted thereon, a gripping jaw extending alongside the fulcrum member and formed with a cam portion having an initial abrupt rise, a cooperating jaw interposed between the first jaw and the fulcrum member and adapted to be backed by the latter whereby the first jaw may be moved against the second jaw for gripping an object, means carried by the fulcrum member for co-acting with the cam portion of the first jaw to effect a closing together of the jaws and then hold them so closed during the lifting of the lever on its fulcrum member to pull on the object, and means for opening the jaws upon reverse movement of the lever.

12. A cotter pin puller comprising a fulcrum member, a lever pivoted thereon, a gripping jaw extending alongside the fulcrum member and formed with a cam portion having an initial abrupt rise, a cooperating jaw interposed between the first jaw

- and the fulcrum member and adapted to be backed by the latter whereby the first jaw may be moved against the second jaw for gripping an object, means carried by the fulcrum member for co-acting with the cam portion of the first jaw to effect a closing together of the jaws and then hold them so closed during the lifting of the lever on its fulcrum member to pull on the object, a stop 5 on the fulcrum member, and a laterally extending finger on said second jaw for engaging the stop to open the jaws when the lever is moved in the opposite direction.
13. A cotter pin puller comprising a fulcrum member, a lever pivoted thereon, a jaw lever pivoted to the first lever, a jaw provided on the second lever opposite the fulcrum member, a cooperating jaw between the fulcrum member and the first jaw pivotally connected to the latter, and means for closing and opening the jaws upon relative closing and opening movements of the levers.
14. A cotter pin puller comprising a fulcrum member, a lever pivoted thereon, a jaw lever pivoted to the first lever, a jaw provided on the second lever opposite the fulcrum member, a cooperating jaw between the fulcrum member and the first jaw pivotally connected to the latter, said fulcrum member being channeled to receive the second jaw, and means carried by the fulcrum member for opening and closing the jaws.
15. A cotter pin puller comprising a fulcrum member, a lever pivoted thereon, a jaw lever pivoted to the first lever, a jaw provided on the second lever opposite the fulcrum member, a cooperating jaw between the fulcrum member and the first jaw pivotally connected to the latter, said fulcrum member being channeled to receive the second jaw, means carried by the fulcrum member for cooperation with the first jaw to effect a closing together of the two jaws, and means for swinging the second jaw away from the first jaw when the two jaws have been released by said first means.
16. A cotter pin puller comprising a pair of pivotally connected jaws, a lever connected thereto, a fulcrum member guidingly embracing the jaws, and a lever connected to the fulcrum member and pivoted to the first lever.
17. A cotter pin puller comprising a casting-like fulcrum member, a handle, connected thereto, cooperating gripping jaws guided in the member, and a handle pivoted to the first handle for sliding the jaws in the member.
18. A pulling tool comprising a pair of handles, a member connected to one handle, a pair of jaws slidably guided by the member and operable by the other handle, and means for closing the jaws upon an article.
19. A cotter pin extractor comprising pivotally connected jaws, a member slidably related to the jaws, means for sliding the member relative to the jaws, and means for operating the jaws by and during the relative sliding movement of said member, and to engage an article therebetween.
20. A cotter pin puller comprising a fulcrum member, a handle connected thereto, a gripping jaw extending alongside the fulcrum member and formed with a cam portion, and a cooperating jaw interposed between the first jaw and the fulcrum member and adapted to be backed by the latter whereby the first jaw may be moved against the second jaw for gripping an object, said fulcrum member having means for coacting with the cam portion of the first jaw to effect a closing together of the jaws and then hold them so closed during the lifting of the lever on its fulcrum member to pull on the object.
21. In a hand tool, a pair of opposed article engaging members one of which is movable toward and away from the other, a guiding member for supporting and guiding said pair of members, said guiding member and said pair of members being longitudinally slidably relatively to each other, means to move said guiding member relatively to said pair of members and means operable by said guiding means during the aforesaid relative longitudinal sliding movement to move said pair of members toward each other.
22. In a hand tool, a slidable member having a free end, said end being adapted to engage an article holding another article to be removed therefrom, a lever pivoted to said member, a pair of article engaging jaws, means to connect said jaws together and to said lever, means associated and slidably with said member to operably engage said jaws to cause them to engage an article therebetween, and means to move said members and said jaws in opposite directions whereby the article engaged by the free end of said member is separated from the article engaged by said jaws to remove the latter article from the former.
23. A hand tool for withdrawing a pin or the like from a member holding the same comprising a pair of jaws adapted to grip a pin or the like, a part adapted to abut the member holding the pin, means to produce a relative movement between the pair of jaws and said part in a longitudinal direction with respect to the pin, and cooperating means between said jaws and said part operative by and substantially at the beginning of the aforesaid movement to close said jaws upon the pin.
24. In a hand tool, a pair of opposed article engaging members, one of said members being movable toward and away from the other, a guiding member for supporting

and guiding said pair of members, said guiding member and said pair of members being longitudinally slid able relatively to each other, means to move said guiding member relatively to said pair of members, means operable by said guiding means during its longitudinal sliding movement to move said pair of members toward each other to engage an article therebetween, and cooperat-

ing means between one of said pair of members and said guiding means and operable during the sliding movement of said guiding means to move said pair of members away from each other to release an article from engagement therewith. 10
15

In testimony whereof I affix my signature.

WILLIAM H. BURKE.
